AUXILIARY CONTACT ASSEMBLY

Ralph B. Immel, Wilkinsburg, Pa., assignor to
Westinghouse Electric Corporation, East Pitts-
burgh, Pa., a corporation of Pennsylvania

Application October 12, 1948, Serial No. 54,098

19 Claims. (Cl. 200—166)

1

My invention relates to electromagnetic contactors and more particularly to auxiliary contact assemblies or interlocks associated with such contactors.

One broad object of my invention is the provision of auxiliary contact assemblies or interlocks for electromagnetic contactors that shall be simple, reliable, and above all considerably cheaper and also more flexible in use.

Another broad object of my invention is the provision of an auxiliary contact assembly, for electromagnetically actuated contactors, which is useful either as a normally open contact or a normally closed contact without requiring any additional parts.

A still further object of my invention is the provision of an auxiliary contact assembly, for an electromagnetically operated contactor, that may be readily adjusted in its operation both with reference to the time of operation of the main contactor as well as an adjustment for either normally open operation or normally closed operation, or both of such adjustments.

Other objects and advantages will become more apparent from a study of the following specification and the accompanying drawings forming part of my disclosure and in which drawings:

Figure 1 is a side view of my auxiliary contact assembly showing the parts arranged for normally open operation and showing the apparatus in such a position that the main contacts of the magnetic contactor are in the open position;

Fig. 2 is a view similar to Fig. 1, but showing the elements in closed position;

Fig. 3 is a longitudinal sectional view of main portions of the auxiliary contact assembly as arranged in Fig. 1;

Fig. 4 shows a detail;

Figs. 5 and 6 are side views of the operating arm for the auxiliary contact assembly, with the actuating element shown in two positions of adjustment in the two views;

Fig. 7 is an enlarged perspective view in vertical section of the upper end of the operating arm showing in Fig. 5;

Fig. 8 is a view similar to the showing in Fig. 1 but with the auxiliary contact assembly arranged for normally closed operation;

Fig. 9 is a showing of the subject matter of Fig. 8 but showing the elements in closed position;

Fig. 10 is a longitudinal sectional view of the main portions of the auxiliary contact assembly as arranged in Fig. 8, and

Fig. 11 is a plan view of a modified contact and terminal connector, showing the part in position on a broken-out portion of its mounting of insulating material.

In Figures 1, 2, 8 and 9, the base 1 comprises the metal or other backing of the electromagnetic

2

contactor, not shown as a whole. To this base 1 is secured the support 2 of insulating material. This support carries the main portions of the auxiliary contact assembly.

Support 2 is mounted by means of suitable screws or bolts 33 and 34 to the forward side of the main contactor, or electromagnetic contactor. This main contactor has an arm 3 secured to its armature, not shown. Actuation of the main contactor causes the contactor arm 3 to swing counterclockwise upon closing of the main contactor and clockwise, by gravity or by spring bias upon release of the armature.

The arm 3 carries a laterally projecting bar 4 to which the auxiliary contact operating arm 14 is rigidly secured. The securing means comprise the bolts 5, lock washers 8 and the nuts 13.

The upper end of the operating arm 14 is provided with a hexagonal recess 24. Into this recess the hexagonal plunger 15 is disposed in fitting relation. The forward surface of the plunger has an annular recess, as shown, for receiving the compression spring 16. The plunger 15 in effect constitutes the head of the bolt 25. The

spring 16 is disposed about the bolt and between the bottom of the recess 24 and the bottom of the annular recess in the plunger. The threaded end of the bolt 25 is provided with the nut 17. This nut 17 is also hexagonal and normally fits

30 into a matching hexagonal recess at the upper forward surface of arm 14. The rearward projection of the plunger 15 may be adjusted to take the positions shown in either Fig. 5 or 6 or any intermediate position. The adjustment of plunger

35 15 is effected by merely depressing the plunger 15 against the compressive force of the spring 16. This operation causes nut 17 to move out of its recess. This nut may then be turned to any position within the adjustment range provided.

40 After the adjustment is made, the plunger 15 is released so that nut 17 falls into its recess. The spring 16 thus holds all parts in the desired position of adjustment.

The auxiliary contact assembly includes two 45 blocks 40 and 41 of insulating material. The block 40 may be considered U-shaped with the U being very shallow. The block 41 is distinctly U-shaped as is readily apparent from Figs. 1, 2, 3, 8, 9 and 10.

These blocks are so disposed in relation to each other that the ends of the legs as 42 and 43, abut against each other and legs 44 and 45 abut against each other as shown to form a contact chamber between the legs, as shown.

55 The end surface of each leg is provided with a shallow groove 46 rectangular in shape at each end, and bulged out to a generally circular shape at its middle, all as more clearly apparent from the showing in Fig. 11. The outward side surfaces of the legs 43 and 45 are each provided

with a rectangular notch 47 for receiving the body portion 48 of the contact strips 49 having the contact button 50 on its inner arm 51 and the terminal connector 52 on the outer arm 53.

The middle or generally circular portion of the contact strip is provided with a generally circular hole 54 disposed to register with the holes 55 and 56 disposed axially of each of the legs 42 and 43, and 44 and 45. In mounting the two U-shaped blocks of insulation 40 and 41, the bolts 19 are disposed in the holes 54, 55 and 56. The grooves 46 in each end surface is selected to have a depth about one-third the thickness of the contact strips 49. This means when the nuts 19' are tightened to firmly hold the blocks 40 and 41 on the support 2, the contact strips 49 are firmly gripped in the grooves 46. This will be readily apparent from a study of Figs. 1, 2, 8 and 9.

The block 40 is, at its outer mid region provided with a cylindrical projecting boss 60 and the block 41 is provided with a similar boss 61 in a similar position. The block 41 is provided with a cylindrical boss 62 at the base of a transverse slot in the bight region of the U-shaped block 41. These bosses 60, 61 and 62 provide seats for compression springs 9 and 59.

The blocks 40 and 41 are provided with rectangular holes axially of the bosses 60, 61 and 62 for receiving the rectangular strip 63. This strip 63 is provided with a pair of arms 64 projecting from the edges. A contact button bridging member 65 having a spring receiving boss 66 at its rear mid region and a pair of contact buttons at the front ends for coaction with the contact buttons 50.

The rectangular member 63 fits fairly loosely into the rectangular openings or holes axially of the bosses 60, 61 and 62. The boss 66 is also provided with a rectangular opening axially of the boss to provide a fairly loose mounting of the member 65 on the rectangular strip 63.

The front end 67 of the strip 63 is provided with a transverse hole for receiving the pin 7. A saucer shaped spring stop 6 is thus held in position on the strip 63. To mount the pin 7, the stop 6 is moved axially against the spring bias until the axis of the transverse hole in the end 67 clears the stop 6 and then the pin 7 is inserted. When the spring 9 moves the stop 6 to the position shown, then the pin 7 is prevented from falling out by the cylindrical side walls of the stop 6.

In Fig. 1 block 40 is mounted adjacent the support 2 with the contact strips 49 in the position, namely, so that the contact buttons at the inner ends of the strips 49 face the front, or left, as seen in Fig. 1. The bridging member 65 is disposed on the strip 63 to the right, or front, side of the arms 64. Spring 59 is disposed in the position shown and thus biases the bridging member 65 against the arms 64. The spring 9 is selected to have a larger force than spring 59. The result will be that the bridging member 65 will be remote from the contact buttons on strips 49, and a normally open interlock is provided for the main contactor.

When the main contactor is operated the arm 14 is moved counterclockwise with the result that plunger 15 engages the end 67. The time of such engagement with reference to the full movement of arm 14 is determined by the plunger adjustment on arm 14. The operation of strap 63 axially compresses spring 9. Spring 59 is expanded, but what is more important the bridging member

65 interconnects the contact straps 49 as shown in Fig. 2.

When it is required to change the interlock to a normally closed contact, then block 41 is mounted adjacent the support 2. The elements, comprising the projecting arms 64, contact strips 49, spring 59, bridging member 65, blocks 40 and 41, and strap 63, all remain in the same relative position but the spring 9 is shifted to the other end of strap 63. Elements 6 and 7 are also so shifted. The spring 9 is then disposed between the back of the saucer shaped spring stop 6 backed by pin 7 and the boss 60 now facing the front.

The terminals 52 are also turned on the contact strip to make the head of the screw in each of the terminals face forward.

Upon operation of the arm 14 counterclockwise the plunger 15 again moves the strap 63 axially but now the arms 64 move the bridging member 65 from the position shown in Fig. 8 to the position shown in Fig. 9.

To facilitate the mounting of my interlock for either a make interlock or a break interlock, I place the abbreviated word Norm. on the flat surface 70 and the word Open on the surface 71. On surface 72 I place the word Norm., not shown, and on surface 73 the word Closed, also not shown.

With the parts thus identified, it is apparent that change from one type of interlock to another type is greatly facilitated and the chance of error is reduced to substantially nothing.

I am well aware that many types of interlocks are known in the trade, but I have not been apprised of any interlock utilizing so few relatively standard parts, and parts that can be so readily interchanged. All of the auxiliary contact or interlock assemblies of the prior art known to me were assembled specifically either for normal open operation or for normal closed operation. Once an auxiliary contact unit had been assembled, it could not be converted from a normally open to a normally closed assembly, as the parts for each assembly were not the same.

The prior art devices were thus expensive and not flexible in use, because it was necessary to make and stack a large number of parts. This was not only a disadvantage to the manufacturer but proved very inconvenient to the user. In general it was easier from an operational point of view to resort to the expense of buying a complete new assembly each time a change-over was required, or a repair was needed.

While I have shown but one main embodiment and some details, I do not wish to be limited by the detail shown and described but only such limitations are to be considered as are embodied in the claims hereto appended.

I claim as my invention:

1. In an electrical interlock, in combination, a base, a support of insulating material mounted on the base, a U-shaped member disposed with its outer bottom of the U against the support, a second U-shaped member having its legs disposed in aligned relation to the first U-shaped member, contact strips between the aligned legs ending in contact buttons in the region between the legs, said U-shaped members being provided with aligned openings in the bights of each U, a rigid strap mounted loosely but non-rotatably in said opening so that said strap may be moved longitudinally, said strap being provided with projecting stops, a contact button bridging bar mounted on the strap, spring means mounted on the strap

between the inner bight of the second U-shaped member and said bar to bias said bar against said projecting stops, spring retaining means near the outer end of the strap, and spring means disposed on the strap between said spring retaining means and the outer surface of the bight of the second U-shaped member for biasing said strap to its outer, or most forward, position to thus hold said bar remote from the contact buttons.

2. In an electrical interlock, in combination, a base, a support of insulating material mounted on the base, a U-shaped member disposed with its outer bottom of the U against the support, a second U-shaped member having its legs disposed in aligned relation to the first U-shaped member, contact strips between the aligned legs ending in contact buttons in the region between the legs, said U-shaped members being provided with aligned openings in the bight of the U, a rigid strap mounted loosely but non-rotatably in said opening so that said strap may be moved longitudinally, said strap being provided with projecting stops, a contact button bridging bar mounted on the strap, spring means mounted on the strap between the inner bight of the second U-shaped member and said bar to bias said bar against said projecting stops, spring retaining means near the outer end of the strap, and spring means disposed on said strap between said spring retaining means and the outer surface of the bight of the second U-shaped member for biasing said strap to its outer, or most forward position to thus hold said bar remote from the contact buttons.

3. In an electrical interlock for an electromagnetic contactor, in combination, a support for said interlock secured to the contactor, a short-legged U-shaped member, a long-legged U-shaped member, said members being disposed toward each other so that the open ends of the U's face each other and the legs are in alignment, contact strips between the ends of the legs, means for firmly mounting the U-shaped members, in the mentioned relation to each other, on said support with the inner ends of the contact strips being disposed in aligned spaced relation in the space between the legs and forming contact buttons, a strap mounted for axial movement in aligned apertures in the bights of the U-shaped members, a contact bridging bar mounted on the strap, and spring means on the strap for biasing said bar to one position with reference to said contact buttons.

4. In an electrical interlock for an electromagnetic contactor, in combination, a support for said interlock secured to the contactor, a short-legged U-shaped member, a long-legged U-shaped member, said members being disposed toward each other so that the open ends of the U's face each other and the legs are in alignment, contact strips between the ends of the legs, the ends of said legs being provided with grooves having, for each pair of aligned legs, a combined depth less than the thickness of said contact strips, means for firmly mounting the U-shaped members, in the mentioned relation to each other, on said support to thus firmly hold said contact strips in said grooves with the inner ends of the contact strips being disposed in aligned spaced relation in the space between the legs and forming contact buttons, a strap mounted for axial movement in aligned apertures in the bights of the U-shaped members, a contact bridging bar mounted on the strap, and spring means on the strap for biasing said bar to one position with reference to said contact buttons.

strap for biasing said bar to one position with reference to said contact buttons.

5. In an electrical interlock for an electromagnetic contactor, in combination, a support for said interlock secured to the contactor, a short-legged U-shaped member, a long-legged U-shaped member, said members being disposed toward each other so that the open ends of the U's face each other and the legs are in alignment, contact strips between the ends of the legs, means for firmly mounting the U-shaped members, in the mentioned relation to each other, on said support with the inner ends of the contact strips being disposed in aligned spaced relation in the space between the legs and forming contact buttons, a strap mounted for axial movement in aligned apertures in the bights of the U-shaped members, a contact bridging bar mounted on the strap, and spring means on the strap for biasing said bar to one position with reference to said contact buttons.

6. In an electrical interlock for an electromagnetic contactor, in combination, a support for said interlock secured to the contactor, a short-legged U-shaped member, a long-legged U-shaped member, said members being disposed toward each other so that the open ends of the U's face each other and the legs are in alignment, contact strips between the ends of the legs, the ends of said legs being provided with grooves having, for each pair of aligned legs, a combined depth less than the thickness of said contact strips, means for firmly mounting the U-shaped members, in the mentioned relation to each other, on said support to thus firmly hold said contact strips in said grooves with the inner ends of the contact strips being disposed in aligned spaced relation in the space between the legs and forming contact buttons, a strap mounted for axial movement in aligned apertures in the bights of the U-shaped members, a contact bridging bar mounted on the strap, and spring means on the strap for biasing said bar to one position with reference to said contact buttons.

7. In an electrical interlock for an electromagnetic contactor, in combination, a support of insulating material mounted in fixed relation to the contactor, a relatively shallow U-shaped member of insulating material, a relatively deeper U-shaped member of insulating material, said U-shaped members having legs of generally the same sectional contours and dimensions and being directed toward each other in aligned relation, holes axially of the legs, a groove rectangular at its ends and bulging into a circular shape near the middle, cut across each of the ends of the legs, two contact strips, one disposed to fit into each pair of contiguous grooves, said contact strips being bulged into circular shape in the region of the circular portion of the groove, each of said contact strips being provided with a circular hole in the axis of the circular bulged portion, retaining bolts disposed through the holes axially of the legs and the holes in the contact strips and engaging the support to firmly hold the U-shaped members and the contact strips on the support, said contact strips being provided with spaced contact buttons in the region between the legs and being provided with terminal connectors at the outer ends, said U-shaped members being provided with rectangular aligned holes through the bights, an elongated strap disposed loosely in the rectangular holes for axial movement in the rectangular

holes, and a contact bridging bar on the strap in the region between the legs.

8. In an electrical interlock for an electromagnetic contactor, in combination, a U-shaped member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections, a spring stop on the end of the strap below the U, and a spring between said stop and the outer bottom of the U biasing said strap and bar toward the inner bottom of the U.

9. In an electrical interlock for an electromagnetic contactor in combination, a U-shaped member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections to move the bar to bridge said contact buttons, a bridge bar secured to the ends of the legs having an opening for receiving the end of the strap projecting from the open end of the U, a spring stop on the end of the strap remote from the open end of the U, and a spring between the stop and the bridge bar for biasing the strap and thus the contact bar to bridge the contact buttons.

10. In an electrical interlock for an electromagnetic contactor, in combination, a U-shaped member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections to move the bar to bridge said contact buttons, a bridge bar secured to the ends of the legs having an opening for receiving the end of the strap projecting from the open end of the U, a spring stop on the end of the strap remote from the open end of the U, and a spring between the stop and the bridge bar for biasing the strap and thus the contact bar to bridge the contact buttons.

11. In an electrical interlock for an electromagnetic contactor, in combination, a U-shaped

member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections to move the bar to bridge said contact buttons, a bridge bar secured to the ends of the legs having an opening for receiving the end of the strap projecting from the open end of the U, a spring stop on the end of the strap remote from the open end of the U, and a spring between the stop and the bridge bar for biasing the strap and thus the contact bar to bridge the contact buttons.

12. In an electrical interlock for an electro-
25 magnetic contactor, in combination, a U-shaped
member, a contact strip mounted in the end face
of one leg of the U-shaped member and having
a contact button facing the bight of the U, a
similar contact strip in the end face of the other
30 leg and having a similar contact button similarly
disposed, said buttons being thus disposed in
spaced relation between the legs, a contact bar
for bridging the contact buttons, a strap disposed
for axial movement in an aperture in the bight
35 of the U, said strap having transverse projections
in the space between the legs and below the con-
tact buttons, said bar being disposed on the strap
below the transverse projections, a spring between
the bar and the bottom of the bight of the U bias-
40 ing said bar against said transverse projections to
move the bar to bridge said contact buttons, a
bridge bar secured to the ends of the legs having
an opening for receiving the end of the strap pro-
jecting from the open end of the U, a spring stop
45 on the end of the strap remote from the open
end of the U, and a spring between the stop and
the bridge bar for biasing the strap and thus
the contact bar to bridge the contact buttons.

13. In an electrical interlock for an electro-
50 magnetic contactor, in combination, a U-shaped member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed
55 for axial movement in an aperture in the bight of the U, said strap having transverse projections in the space between the legs and below the contact buttons, said bar being disposed on the strap below the transverse projections, a spring between the bar and the bottom of the bight of the U bias-
60 ing said bar against said transverse projections, a spring stop on the end of the strap below the U, and a spring disposed between said stop and the outer bottom of said U biasing said strap and bar toward the inner bottom of the U.

70 14. In an electrical interlock for an electro-
75 magnetic contactor, in combination, a U-shaped
member, a contact strip mounted in the end face
of one leg of the U-shaped member and having
a contact button facing the bight of the U, a
similar contact strip in the end face of the other

leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections, a spring stop on the end of the strap below the U, and a spring disposed between said stop and the outer bottom of said U biasing said strap and bar toward the inner bottom of the U.

15. In an electrical interlock for an electromagnetic contactor, in combination, a U-shaped member, a contact strip mounted in the end face of one leg of the U-shaped member and having a contact button facing the bight of the U, a similar contact strip in the end face of the other leg and having a similar contact button similarly disposed, said buttons being thus disposed in spaced relation between the legs, a contact bar for bridging the contact buttons, a strap disposed for axial movement in an aperture in the bight of the U, said strap having transverse projections in the space between the legs and below the contact buttons, said bar being disposed on the strap below the transverse projections, a spring between the bar and the bottom of the bight of the U biasing said bar against said transverse projections, a spring stop on the end of the strap below the U, and a spring disposed between said stop and the outer bottom of said U biasing said strap and bar toward the inner bottom of the U.

16. In an electrical interlock, in combination, a base, a support mounted on the base, an elongated member of insulating material disposed on the support so that one side is against the support, said member having raised flat portions at each end on the side opposite to the support, a second somewhat similar elongated member having similar raised flat portions, so disposed on the first member that the flat end portions are contiguous, contact strips between the contiguous surfaces of the flat portions ending in contact buttons in the region between the mid-portions of the two members, aligned openings in the mid-portions of the members, a strap mounted for longitudinal motion but non-rotatably in the openings, said strap being provided with shoulders, a contact bridging bar mounted on the strap, spring means mounted to bias the contact bar against the shoulders, spring retaining means between the outer end of the strap and the outer surface of the second member, and spring disposed on the strap between the spring retaining means and the outer surface of the second member for biasing said strap to a position to hold the bar remote from the contact buttons.

17. In an electric interlock, in combination, a base, an inner arcuate member of insulating material mounted on the base with the concave portion of the arc facing away from the base, a somewhat similar outer arcuate member, disposed in an opposite sense with reference to the base, on the first member, contact straps disposed between the registering ends of the members projecting inwardly to form spaced aligned contact buttons between the members, aligned openings in the members, the alignment being transverse of the aligned contact buttons, a strap disposed

for slidable non-rotary movement in the openings, said strap having projecting lugs near the middle thereof, a contact bar for bridging the contact buttons provided with a transverse opening for receiving the strap, a biasing spring being selectively positionable in the order named either between the lugs on the strap and the outer arcuate member, or between the lugs on the strap and the inner arcuate member, spring means engaging the strap to bias the strap outwardly.

18. In an electric interlock, in combination, a base, an elongated block of insulating material thicker at each end than in the middle mounted on the base, a second somewhat similar elongated block of insulating material mounted on the first member, the members by reason of their thicker ends being shaped to have end-engagement with each other at corresponding ends and to form a space between the members at generally the mid-portion of the members, aligned openings at the mid-portions, contact straps disposed between the engaging ends projecting into the space to form a pair of spaced contact buttons, a strap mounted for slidable motion in the openings, said strap having transverse projections and being long enough that the ends of the strap project beyond the non-contiguous surfaces of the members with the transverse projections disposed in the space between the members, a contact bridging bar disposed on the strap adjacent the projections, a spring coacting with one of the bridging members and the contact bridging bar to bias the bar against the transverse projections, and spring means for biasing the strap toward one end position.

19. In an electric interlock, in combination, a base, an elongated block of insulating material thicker at each end than in the middle mounted on the base, a second somewhat similar elongated block of insulating material mounted on the first member, the members being shaped by reason of their thicker ends to have end-engagement with each other at corresponding ends, and to form a space between the members at generally the mid-portion of the members, aligned openings at the mid-portions, contact straps disposed between the engaging ends projecting into the space to form a pair of spaced contact buttons, a strap mounted for slidable motion in the openings, said strap having transverse projections and being long enough that the ends of the strap project beyond the non-contiguous surfaces of the members with the transverse projections disposed in the space between the members, a contact bridging bar disposed on the strap adjacent the transverse projections, a spring disposed about the strap and coacting with one of the bridging members and the contact bridging bar to bias the contact bridging bar against the transverse projections, spring retaining means at the outer end of the strap, and a spring between the spring retaining means and the outer bridging member to bias the strap outwardly.
